UNITED STATES PATENT OFFICE

GEORGE H. PERKINS, OF PHILADELPHIA, PENNSYLVANIA, ASSIGNOR TO HIMSELF, JOSEPH LE COMTE, OF NEW YORK CITY, AND ATLANTIC REFINING COMPANY, OF PHILADELPHIA, PENNSYLVANIA.

IMPROVEMENT IN APPARATUS FOR FACILITATING THE CONVEYANCE AND DELIVERY OF BOXES.

Specification forming part of Letters Patent No. 177,553, dated May 16, 1876; application filed April 19, 1876.

To all whom it may concern:

Be it known that I, GEORGE H. PERKINS, of Philadelphia, Pennsylvania, have invented an Improved Apparatus for Facilitating the Conveyance and Delivery of Boxes, of which the following is a specification:

My invention relates to certain improvements in devices for the conveyance and delivery of boxed cans containing petroleum or similar liquid; and the objects of my improvements are, first, to facilitate the placing of the box on the conveyer; second, to regulate its descent along the same; third, to mark the box during its passage; and, fourth, to provide for the direct delivery of the box onto the deck of a vessel, or for its storage in a suitable apartment.

These objects I attain in the manner which I will now proceed to describe, reference being had to the accompanying drawing, in which—

Figure 1, Sheet 1, is a plan view of part of my improvements; Fig. 2, an enlarged sectional view of a portion of the same; Fig. 3, a transverse vertical section on the line 1 2; Fig. 4, Sheet 2, a transverse vertical section, drawn to an enlarged scale, of a portion of the device not shown in Fig. 1; and Fig. 5, a plan view of Fig. 4.

X X represent portions of two ways along which the boxed cans slide after their lids have been secured, as described in a former application for a patent filed by me on the 6th day of November, 1875.

A A are two parallel ways, which are somewhat closer together than the ways X X, but which form continuations of the same. These ways are gradually inclined downward from the point x, where the box is received, to the point y, at which it is discharged, so that the box resting upon the anti-friction rollers a shall traverse the ways by gravity alone. At the junction of the ways X and A is a platform, b, and a pit, d, the surface of the former being provided with a number of small rollers, e, arranged at different angles in respect to the line of the ways, and the bottom of the pit being covered with sawdust or other yielding material. To one of the ways

A, at a point adjacent to the pit d, is hung a lever, B, connected by means of a cord or chain, c, to a lever, C, which is arranged at a considerable distance from the lever B, and is connected to a lever, C', attached by means of suitable cords or chains to the ways A A, which, for some distance on either side of this point, are capable of yielding, and can, by operating the lever B, be made to approach and bind upon the sides of the boxes, thus preventing their further descent. Upon releasing the lever the yielding ways will spring apart, and the lever C will be retracted, owing to the action upon its outer end, of a cord, f, having a weight, f', for imparting the proper tension to the same. To insure the action of this braking device upon a larger area of the boxes, as well as to prevent excessive wear upon the ways, the latter are furnished with strips E, secured to their upper edges. At a point still further down the ways is arranged the marking device shown in Figs. 4 and 5, Sheet 2. This consists of a marking-wheel, g, having formed upon its periphery the proper characters, this wheel sliding vertically in bearings in the ways, and bearing at the lower edge upon the periphery of an inking-wheel, h, which has its bearings in the end of a spring-bar, F, secured to the ways, and turns in an ink-bag, i, from which it derives its supply, the surplus ink being removed from the periphery of the wheel by a brush, i', before it comes in contact with the periphery of the marking-wheel g. At a point beyond the inking device just described ways H extend from one of the ways A to the floor of a store-house, and to these ways is adapted a sliding carriage, I, to which is attached one end of a cord, m, which passes round a roller, n, turning in bearings p, secured to the ways, and is attached at its opposite end to the end of a spring-bar, J, secured to the floor of the store-house. On this cord near the end is hung a weight, r, and at a point somewhat higher up a weight, s, both these weights, when the carriage I is at the top of the ways H, resting upon the floor, but being raised as the said carriage descends. To one of the ways A, immediately adjacent to this unloading de-

vice, is hung an arm, *t*, Fig. 1, which can be so acted upon by a cam-lever, *u*, that it will be forced against the side of the box on the way, and stop its movement. From this point the ways lead direct to the deck or side of a vessel which is to be loaded with the boxes.

The operation of the above-described device is as follows: A box from the ways *X* is received upon the table *b*, and is then seized by an attendant, and turned to the position shown by dotted lines in Fig. 1, this movement being facilitated by the rollers *e*. The box is then turned over, so that its end rests on the sawdust in the pit *d*, and is then again turned, as shown by dotted lines in Fig. 2, and laid top downward on the rollers *a* of the ways *A*. As it traverses down these ways, any leak caused by the puncture of the can in nailing on the lid can be easily detected, and the defective box removed. The box moves slowly along the ways until it arrives at the flexible portion of the same, when the attendant operates the lever *B*, thus drawing together the said flexible portion of the ways and their strips *E*, and causing them to clamp and hold the box.

The box is thus held until the ways between it and the lever *B* become filled with boxes, when said lever is released, and a number of boxes are allowed to pass on. After a certain number have passed beyond the control of the brake, however, the latter is again tightened, and the descent of the rest of the boxes is stopped until the space thus cleared at the head of the ways *A* is again filled with boxes, when the operation is repeated.

By thus maintaining on the ways a line of boxes in contact with each other, and by releasing a few at a time, the tendency of the boxes to strike forcibly against each other and endanger the contents is prevented.

The boxes which have been released by the brake move down the ways, and pass over the printing-wheel *g*, by which the proper names or characters are marked upon the lids of the boxes. The latter then continue their movement directly to the ends of the ways, if it is desired to deliver the boxes upon the deck or at the side of a ship.

If the boxes are being delivered too fast, an attendant moves the cam-lever *u* so as to bind the arm *t* against the box opposite to it, and thus stop its descent until the boxes in front have been disposed of.

If it is not desired, however, to deliver the boxes directly on ship-board, an attendant standing upon a platform adjacent to the ways *H*, seizes the first box that descends the ways, and, turning it over the edge, lets it fall onto the carriage *I*, upon which it is supported by

the lip at the bottom. The weight of the box causes the descent of the carriage *I* until it lifts the weight *s*, which balances the weight of the box, and prevents the further descent of the carriage. As the next box arrives it is turned over upon the box already on the carriage, thus causing its further descent until counterbalanced by the weight *r*. Upon the third box being placed upon the carriage the latter descends to the bottom of the ways *H*, the descent being gradual, however, owing to the action upon the end of the cord *m* of the spring-bar *J*.

The boxes are now in position for the insertion beneath the lowermost box of the nose of a truck, as shown by dotted lines, onto which the boxes are tilted, and on which they are conveyed to the point at which they are to be stored.

As soon as the boxes are removed the weights *r* and *s* fall, and draw the carriage *I* to the top of the ways *H*, preparatory to receiving another load.

It will be seen that the entire operation above described necessitates very little handling of the boxes, and is continuous, the boxes being delivered as fast as they are received from the ways *X*.

I claim as my invention—

1. The combination of the ways *X* and *A*, with the table *b* and its rollers *e*.
2. The combination of the table *b* and ways *A* with the pit *d*.
3. The inclined ways *A*, combined with braking appliances, by which the descent of the boxes may be retarded or stopped, as described.
4. The combination of the yielding portions of the ways and their strips *E* and the lever *B*, with devices substantially as described, by which, upon the movement of said lever *B* the ways are caused to approach each other, as set forth.
5. The combination of the ways *A*, down which the box slides, with the marking-wheel *g*.
6. The combination of the ways *A* with the ways *H*, and the sliding carriage *I*, the descent of which is regulated by a spring or weight.
7. The combination of the carriage *I* and its cord *m*, with the roller *n*, weights *r* and *s*, and spring-bar *J*.

In testimony whereof I have signed my name to this specification in the presence of two subscribing witnesses.

GEO. H. PERKINS.
